UNITED STATES PATENT OFFICE.

CISCO BULLIVANT, OF SPOKANE, WASHINGTON, ASSIGNOR OF ONE-HALF TO WALTER W. ZENT, OF SPOKANE, WASHINGTON.

RIM CONTRACTOR AND EXPANDER.

1,306,997.

Specification of Letters Patent. Patented June 17, 1919.

Application filed October 18, 1916. Serial No. 126,561.

To all whom it may concern:

Be it known that I, CISCO BULLIVANT, a citizen of the United States, residing at Spokane, in the county of Spokane and State of Washington, have invented new and useful Improvements in Rim Contractors and Expanders, of which the following is a specification.

This invention relates to improvements in means for reducing and expanding split demountable tire rims.

This invention is an improvement on the device disclosed in my pending application filed September 19, 1916, Serial No. 121,022.

In my former device it was the object to differentially act upon the split terminals to first separate them, and thereafter telescope these terminals in order to reduce the diameter of the rim. I found, in practice

that while the operation of removing and taking off a tire was greatly facilitated by my former device, still, in many instances difficulty was encountered in expanding so as to return the split terminals into their initial abutting relation. While the resiliency of a rim will cause it to automatically expand, when released, to a nearly complete initial position, this resiliency cannot be relied upon for completely and finally returning the split ends into abutting relation.

It is the object of my present improved device to not only differentially act upon the split terminals to first radially separate and then contract the same, but also, to subsequently differentially act upon the split terminals to expand the same into their normal abutting relation position. In the most improved embodiment of my device, this dual function is performed by rod mechanism to which tension is applied for contracting, and compression for expansion.

My invention has other features of novelty which will be more fully described in connection with the accompanying drawing and which will be more particularly pointed out in the appended claims.

In the drawing:

Figure 1 is a view in side elevation of a split rim showing the application thereto of the device of my invention.

Fig. 2 is a sectional view on line 2-2 of Fig. 1 showing the device, or a part thereof, adjusted to contract the rim.

Fig. 3 is a view similar to Fig. 2 showing the device actuated to expand the rim. 55

Fig. 4 is an enlarged detail sectional view on line 4-4 of Fig. 1.

Like characters of reference designate similar parts throughout the different figures of the drawing. 60

My device is shown applied to a modern type of demountable rim having a web or base 1 and tire retaining flanges 2. In this type of rim the split terminals 3 and 4 are not severed on a scarfed or chamfered joint 65 but are split square off and on a radial line so as to present flat abutting ends 5 and 6. In this form of rim, in order to contract the same, it is necessary to first radially separate the ends where the contracting 70 stress applied is substantially radial to the rim, as in the case of my present invention.

Referring more particularly to my improved device, 7 and 8 designate a pair of differential rim breaking and reducing or 75 expanding rods having terminal ends 9 and 10 adapted for endwise abutting relation against the web 1. Said rods are shown provided with pairs of clips or hooks 11 and 12 adapted for engagement with the tire 80 retaining flanges 2 in a manner more particularly shown in connection with an opposite pair of clips, presently to be described,

and illustrated in Fig. 2. Pivot bolts 13 and 14 extend through the clips 11 and 12, and the rods 7 and 8, respectively, to pivotally connect the clips 11 with the rod 7, and the clips 12 with rod 8. Winged nuts 15 and 16 may be applied to the pivot bolts to tightly grip the clips or hooks 10 and 11 85 in frictional engagement with the flanges 2 to prevent slippage of the parts. However, while this tight adjustment is advantageous, it is not absolutely essential to efficient operation. It will be noted that 90 the hooks 11 and 12 are disposed at points on opposite sides of the split terminals of the rim. Rod 7 is shorter than rod 8 and I have shown these rods pivotally connected by a pivot 17. Likewise, the distance between pivot 17 and the extremities of hooks 11 is less than the distance between pivot 17 and the extremities of hooks 12. 95

Now therefore it will be seen that if tension or pulling stress was applied to rods 7 100 and 8 radially inwardly of the rim, by

means of the pivot 17, the terminal 3 would first be drawn inside of terminal 4 and then the two terminals would be telescoped as shown in Fig. 1. Likewise, if compressing 5 or pushing stress were exerted radially outwardly, the rod ends 9 and 10 would be forced into engagement with web 1 and differentially expand the rim so as to force the terminal ends 5 and 6 into abutting relation. 10 Thus it will be seen that either in contraction or expansion the rod devices 7 and 8 act differentially.

An actuating rod device is pivotally connected with the differential rod devices. 15 As shown, said actuating device includes a pivot bolt 18 which is connected with rods 7 and 8 by pivot bolt 17, a winged nut 19 serving to tighten the connection when desired. Bolt 18 is threaded for engagement 20 with a turnbuckle 20, at one end of the latter. A threaded clip bolt 21 engages the other end of the turn buckle and the terminal end 22 of the clip bolt is adapted for engagement with web 1 to act in opposition 25 to rod ends 9 and 10 in order to expand the rim when the turn buckle 20 is rotated in one direction. A pair of clips or hooks 23 is pivoted by a pivot bolt 24 to a reduced portion 25, of bolt 21. A winged nut 26 serves 30 to adjust the hooks 23 tightly against the rim when desired. The clips or hooks 11 and 12 are in all respects similar to the hooks 23. It is preferable to apply the device in a manner similar to the application 35 shown in Fig. 1 so that the longitudinal axis of the actuating rod device will not be in alignment with rod 7, but will be slightly to the left of rod 7, as indicated at α . Thus pivot 17 will be dead center with respect to rod 40 7 and prevent buckling of the device laterally to the right of Fig. 1 under compression or expanding stress applied to the rods. However, the clips 12 would not permit the device to break at pivot 17 after certain play 45 had been taken up.

It will now be clear that by turning the nut 20 in one direction, the rim will be contracted. Under tension stress illustrated, there will be a certain amount of play or 50 space between the rod ends and the rim web, as shown in Fig. 2. When the nut 20 is turned to expand the rim, the first few turns will merely release the rim for expansion under its own inherent resiliency. After 55 this resiliency is exhausted, then further turning of the nut 20 will bring the rod ends into engagement with the rim's web 1, as shown in Fig. 3, and from that point on, the rods will be under compression and will 60 be forced radially outwardly until the ends 5 and 6 have been snapped into position.

It is believed that the novelty and utility of my invention will be fully understood from the foregoing description, and while I 65 have herein shown and described one specific

form of my invention, I do not wish to be limited thereto except for such limitations as the claims may import.

I claim:

1. In a device for contracting and then expanding a split demountable rim, a pair of rim breaking rod devices engageable radially inwardly and outwardly of the rim at points on opposite sides of the split portion thereof, a turn buckle rod device engageable radially inwardly and outwardly of the rim substantially diametrically opposite the split portion thereof, said turn buckle rod device being pivotally connected with said rod breaking devices and one of said rod breaking devices being longer than the other, whereby actuation of the turn buckle device in one direction will draw said rod devices radially inwardly of the rim to first separate the ends and then telescope the rim ends and reduce the diameter of the rim, or, upon actuation of the turn buckle device in an opposite direction forcing said rod devices outwardly radially of the rim to expand the latter to a normal position, substantially as described.

2. As a means for facilitating the application and removal of a tire from a split rim, a single set of grips for engagement with opposite marginal edges of said rim substantially diametrically opposite the split portion thereof, terminal sets of grips for engagement with opposite margins of each split terminal of said rim, a contracting and expanding mechanism having a rod pivotally connected with said single set of grips and extending between said grips and toward and for engagement with the inner face of said rim, a differential rod of relatively long length pivoted to said mechanism at its inner end and its outer end extending between and being pivoted to one set of said terminal grips and the terminal end of said longer rod extending beyond the point of pivotal connection with its terminal grips toward and for engagement with the inner face of said rim, and a relatively short differential rod pivoted to said mechanism at its inner end on an axis co-incident with the pivotal connection of the longer rod to said mechanism and the outer end of said shorter rod extending between and being pivoted to the remaining set of terminal grips and the terminal end of said shorter rod extending beyond its point of pivotal connection with its set of terminal grips toward and for engagement with the inner face of said rim, whereby contraction of said mechanism will impose tension on said rods and their grips to differentially operate on said split terminals to first radially separate and then circumferentially telescope the same, and whereby expansion of said mechanism will impose compression stress on said rods to engage the terminal ends thereof with the

inner face of said rim to first telescopically expand said split terminals and then force the ends of said terminals into abutting relation, the clearance between the terminal 5 ends of said rods and the inner face of said rim being sufficiently reduced to prevent disconnection of said clips from the flange margins of said rim when said mechanism is reversed from contractive to expansive operation or vice versa.

3. As a means of facilitating the application and removal of a casing on and off a split rim, a turn buckle body, a threaded bolt for engagement with one end of said body 15 and having an end for expansive engagement with the inner face of said rim substantially diametrically opposite the split portion thereof, clip means connected with said bolt for contractively engaging said 20 rim, a second threaded bolt for the remaining end of said turn buckle body, a relatively long differential rod pivoted to said

second bolt and having an end for expansive engagement with the inner face of one split terminal of said rim, a relatively short differential rod pivoted to said second bolt and having an end for expansive engagement with the inner face of the remaining terminal of said rim, terminal clip means for each rod for contractive engagement with the terminal 30 ends of said rim, whereby rotative adjustment of said turn buckle body in one direction will differentially operate on said split terminals to first radially separate and then telescopically contract said terminals, and 35 rotative adjustment of said buckle body in another direction will first differentially expand said rim terminals and then force the innermost terminal into abutting relation with the outermost terminal. 40

In testimony that I claim the foregoing as my own, I hereby affix my signature.

CISCO BULLIVANT.
